(57) **CLAIM**

The ornamental design for a guitar headstock, as shown and described.

DESCRIPTION

FIG. 1 is a front view of a design for a guitar headstock.
FIG. 2 is a right side view of a design for a guitar headstock.
FIG. 3 is a bottom end view of a design for a guitar headstock.
FIG. 4 is a back view of a design for a guitar headstock.
FIG. 5 is a left side view of a design for a guitar headstock.
FIG. 6 is a top end view of a design for a guitar headstock.
FIG. 7 is a top right perspective view of a design for a guitar headstock; and,
FIG. 8 is a bottom right perspective view of a design for a guitar headstock.

The broken lines shown throughout the views represent the portions of the guitar headstock, which form no part of the claimed design.
